[57] CLAIM

The ornamental design for an automatic blood pressure
measuring apparatus, substantially as shown.

DESCRIPTION

FIG. 1 is a perspective view of an automatic blood
pressure measuring apparatus showing my new design;
FIG. 2 is an elevation thereof showing the side not
visible in FIG. 1;

FIG. 3 is a front elevational view thereof;

FIG. 4 is a top plan view thereof;

FIG. 5 is a rear elevational view thereof; and,

FIG. 6 is a bottom plan view thereof.
